[57] CLAIM

The ornamental design for a transparent fillable platform shoe, as shown and described.

DESCRIPTION

FIG. 1 is a perspective view from the upper right front of a platform shoe showing my new design;

FIG. 2 is a top plan thereof;

FIG. 3 is a bottom plan thereof;

FIG. 4 is a front elevational view thereof;

FIG. 5 is a rear elevational view thereof; and,

FIG. 6 is a left side elevation thereof, the broken lines showing the shoelaces being for illustrative purposes only and forming no part of the claimed design.
